US0D1069128S

(12) **United States Design Patent** (10) Patent No.: **US D1,069,128 S**
(45) Date of Patent: ** Apr. 1, 2025

(54) **DEVICE FOR DETECTION OF INDUSTRIAL PATHOGENS**

(71) Applicant: **Thenextpangea, S.L.**, Gozón (ES)

(72) Inventor: **Mario Rodríguez Mazón**, Gozón (ES)

(**) Term: **15 Years**

(21) Appl. No.: **35/520,759**

(22) Filed: **Apr. 12, 2024**

(80) **Hague Agreement Data**

Int. Filing Date: **Apr. 12, 2024**

Int. Reg. No.: **DM/236650**

Int. Reg. Date: **Apr. 12, 2024**

Int. Reg. Pub. Date: **May 3, 2024**

(51) **LOC (15) Cl. 24-02**

(52) **U.S. Cl.**

USPC **D24/186**

(57) **CLAIM**

The ornamental design for a device for detection of industrial pathogens as shown and described.

DESCRIPTION

1. Device for detection of industrial pathogens
- 1.1 : Top
- 1.2 : Right perspective
- 1.3 : Left perspective
- 1.4 : Rear perspective
- 1.5 : Bottom perspective
- 1.6 : Left
